Territory of Hawaii

Application February 19, 1946, Serial No. 648,735

2 Claims. (Cl. 123—122)

1

The present invention relates to a fuel feeding system for internal combustion engines.

The principal object of this invention is to provide means for intermixing a suitable quantity of air with a suitable quantity of liquid gasoline and then supplying this mixture to the carburetor of an internal combustion engine together with a separate supply of raw gasoline for maximum engine efficiency.

A second object of the invention is to provide a system for supplying a pre-heated mixture of gasoline vapor and air to the carburetor, said pre-heated mixture comprising substantially dry vapor or gas.

A third object of the invention is to provide a system for feeding fuel to an internal combustion engine which includes a variable-speed pump for mixing pre-heated air and liquid gasoline and then conducting said pre-heated mixture to the carburetor.

A fourth object of the invention is the provision of a tank for liquid gasoline or other similar fuel in which the fuel may be vaporized to form a dry vapor or gas.

A fifth object of the invention is the provision of a fuel feeding system of the character described which is provided with suitable safeguards against the danger of explosion due to backfire and also against the danger of excess fuel pressure.

These and other objects are attained by mechanism illustrated in the accompanying drawing in which—

Fig. 1 is a partly sectional, partly diagrammatic view, of the entire fuel feeding system herein described and claimed; and

Fig. 2 is an enlarged sectional view of the carburetor thereof.

The internal combustion engine 10 is of conventional design as is the exhaust pipe 11 leading from it, the generator 12 controlled by it and the ignition system including the battery 13. The gasoline tank 14, however, is not conventional equipment. Instead, it has two compartments, a smaller compartment 15 and a larger compartment adjacent thereto 16. Both compartments may be filled with ordinary gasoline or with such other fuel as the internal combustion engine 10 may be designed to use, the fuel being introduced into compartment 15

2

through inlet 17 and into compartment 16 through inlet 18. An apertured baffle board 19 is carried within the larger compartment 16 horizontally thereof, above the gasoline 20 therein contained. This baffle board prevents splashing of the gasoline into the upper part of tank compartment 16 and really, in effect, separates said compartment into an upper and a lower compartment communicating with each other through the perforations in the baffle board. A second baffle board 21 is carried within the smaller compartment 15 also horizontally thereof, but unlike the first baffle board mentioned, this baffle board 21 is carried below the surface level of the gasoline 22 contained in said compartment. This second baffle board functions to prevent excessive splashing of the gasoline in compartment 15.

Mounted on the exhaust pipe 11 is an air filter 30 which communicates with larger compartment 16 through a pipe 31. An air pump 32 controls the flow of air from the air filter 30 through the pipe 31 and into compartment 16. The pump 32 is operated by means of a variable speed electric motor 33 which is connected to the battery 13 in the manner hereinafter described. It will be noted that the speed of motor 33 is controlled by a rheostat 34 and that the rheostat, in turn, is controlled by a control lever 35 connected to the throttle control 36. As the throttle is advanced or retarded, the speed of the motor is caused to increase or decrease, thereby providing a greater or lesser flow of air from the filter 30 to the compartment 16 through the pipe 31. An outlet pipe 37 provides communication between the gasoline compartment 16 and the manifold 38 of internal combustion engine 10. Thus it is that when the engine is in operation, the throttle being advanced or retarded, two forces act simultaneously as well as independently to draw air into the filter 30, thence through pipe 31, the compartment 16, the pipe 37 and into the manifold 38, the vacuum created by the engine itself and the pressure of the pump 32.

The system thus far described operates as follows: Air is drawn into the filter 30 and it is pre-heated by contact with the hot exhaust pipe 11. The pre-heated air is then forced into the gasoline compartment 16 under the influence of the pump 32. It will be noted that the pipe 31 ex-

tends down to the bottom of the compartment 16 thereby causing the air passing therethrough to mix very intimately with the gasoline in said compartment. In consequence of such action, a mixture of gasoline and pre-heated air, the mixture taking the form of a dry vapor or gas, is forced up through the outlet pipe 37 and thence into the manifold 38 of the internal combustion engine.

The second part of the system herein claimed makes use of the smaller gasoline compartment 15 and it includes an outlet pipe 40 which provides communication between said compartment 15 and the carburetor 41, the carburetor communicating also with the pipe 37 which leads to the manifold 38. The vacuum generated by the internal combustion engine during the operation of the engine sucks raw gasoline 22 unmixed with air up through the pipe 40, into and through the carburetor 41 and thence through the pipe 37 and into the manifold 38. When the raw gasoline 22 reaches the pipe 37, it is caused to mix with the gasoline-air vapor or gas above described. It is this final mixture that reaches the internal combustion engine.

It will be noted that between the carburetor 41 and the pipe 37 is a butterfly valve 42 which is controlled by the same control member 36 which controls the rheostat control lever 35, so that the speed of the pump 32 always corresponds to the size of the opening provided by the butterfly valve 42, the larger the opening the greater the speed, the smaller the opening the less speed.

To prevent damage from backfiring, a hingedly mounted valve 43 is carried within pipe 37, said valve being normally closed and adapted to open only when the current of gasoline vapor-air mixture is moving in the direction of the internal combustion engine in response to the forces acting upon it as above described. A switch 44 shown diagrammatically in Fig. 1 controls the electric motor 33 which is suitably grounded and operates pump 32. This operation is effected through conductor 45 leading from the motor to the switch 44 and conductor 46 leading to the main cable 47 of the ignition system. This cable is connected by wires 47a, 47b and 47c and back to the battery 13 through a wire 47d and is in parallel with the starter button. A pipe 48 extends from the engine manifold 38 into the closed casing containing the switch 44, and its end is closed and the pipe extends to the bottom of the casing. A lightweight piston 49 is snugly disposed within the chamber or casing around the pipe and is adapted to move up and down therein. Contacts 50 and 51 are spaced apart within the casing and are connected by the metal piston 49 when it is raised. The pipe 48 above the contacts 50 and 51 but within the casing is provided with a small hole 49a. When the engine is operating normally, the suction produced in the pipe 48 and by means of the hole 49a will cause the piston 49 to move up around the pipe 48 and make contact between contacts 50 and 51 thus closing the circuit for the motor. When, however, a backfire occurs the sudden surge of pressure in the manifold will be impressed upon pipe 48 and make itself felt in the casing through the hole 49a to allow the piston 49 to drop and break the circuit.

The cable 47 contains several separate wires such as the wire 46 leading to the battery, and the wire leading from the starting motor to the starting button and not extending through the ignition switch. The several circuits are traced

as follows: From ground on the motor through the motor, along the wire leading therefrom which extends as a separate wire through the cable 47 to the starting button, across the button to one side of the battery, through the battery and then to the battery ground. From ground on fan motor 33, through the motor 33, wire 45, across terminals 50 and 51, wire 46, through the cable 47 as a separate wire, out of cable 47 along wires 47a, 47b, 47c, and 47d to the battery, through the battery to ground. In traversing wires 47a, b, and c, the current passes through control devices which are well known and so little part of the invention that they have not even been numbered. The safety valve 52 communicating with chamber 16 of the gasoline tank affords additional protection against accidents. This valve prevents excessive pressures from building up in chamber 16.

The invention hereinabove described is susceptible of many variations and these variations are herein contemplated.

I claim:

1. A fuel feeding system for internal combustion engines having a carburetor with an air intake port and a gasoline intake port, said system comprising an air heating means consisting of an air filter mounted on the exhaust pipe of the engine, a gasoline tank divided by means of a partition into two compartments, a pipe providing communication between said air filter and one of said tank compartments, consisting of an electric motor-driven air blower connected to said pipe to force heated air from said air filter into said gasoline tank compartment, a rheostat connected to said electric motor, a rod connecting said rheostat to the throttle on the carburetor, whereby opening of the throttle causes an increase in the speed of the electric motor and of the fan connected thereto, said air pipe leading from said air filter extending to the bottom of the gasoline tank compartment to force the heated air to bubble through the gasoline in said compartment to saturate said air with gasoline, a perforated baffle board mounted near the top of said gasoline tank compartment horizontally thereof, said baffle board providing a space at the top of said gasoline tank compartment between said baffle board and the top wall of said tank in which the gasoline saturated heated air may collect, a second pipe communicating between the upper portion of said gasoline tank compartment and the air intake port and the carburetor, whereby the gasoline saturated heated air is adapted to be drawn up into the carburetor, a second compartment in said gasoline tank, and a pipe connecting said second compartment with the gasoline intake port in the carburetor, whereby raw gasoline may be drawn up into the carburetor.

2. A fuel feeding system for internal combustion engines having a carburetor with an air intake port and a gasoline intake port, said system comprising an air preheating means consisting of an air filter connected to the exhaust pipe of the engine, a gasoline tank having an inlet at a point located a predetermined distance from the top of the tank, whereby the tank may be filled only to a predetermined level, a pipe connecting said air filter with the bottom of said tank, a variable speed air blower connected to said pipe, whereby the preheated air may be caused to bubble through the gasoline in said tank, thereby becoming saturated with gasoline, a perforated baffle board mounted in said gasoline tank horizontally thereof above the level of the gasoline

and defining a space between said baffle board and the top wall of the tank wherein the gasoline saturated preheated air is adapted to collect, a pipe providing communication between the air inlet port of the carburetor and said space at the top of the gasoline tank, whereby gasoline saturated air may be drawn into the carburetor, and a second gasoline tank communicating through another pipe with the gasoline intake port of the carburetor, whereby raw gasoline may be drawn into the carburetor.
